UNITED STATES PATENT OFFICE

101,745

DESIGN FOR A STORE

Robert W. Ryle, New York, N. Y., assignor to
Le Bas, Inc., New York, N. Y., a corporation of
New York

Application August 20, 1935, Serial No. 58,206

Term of patent 7 years

To all whom it may concern:

Be it known that I, Robert W. Ryle, a citizen of the United States and resident of New York city, in the county of New York and State of New York, have invented a new, original, and ornamental Design for a Store, of which the following is a specification, reference being had to the accompanying drawing, forming part thereof, in which

Figure 1 is an outside view of the front of the store;

Figure 2 is a plan view of the interior of the store, the lobby and show windows being shown in cross section taken on lines 2—2 of Fig. 1;

Figure 3 is an interior view of the front of the store;

Figure 4 is an interior view of the rear of the store as viewed from the front;

Figure 5 is a right side view of the store taken from the left side;

Figure 6 is a left side view of the store taken from the right side;

Figure 7 is a perspective view of the interior of the store taken angularly across from the right rear to the left front; and

Figure 8 is an enlarged plan view of the lobby and show windows shown in Figure 1.

I claim:

The ornamental design for a store, as shown and described.

ROBERT W. RYLE.
